UNITED STATES PATENT OFFICE

HARRY S. HUMPHREYS, OF LANCASTER, PENNSYLVANIA, ASSIGNOR TO ARMSTRONG CORK COMPANY, OF LANCASTER, PENNSYLVANIA, A CORPORATION OF PENNSYLVANIA

EMBOSSING LINOLEUM

Application filed October 30, 1929. Serial No. 403,600.

This invention relates to the manufacture of embossed linoleum and is applicable either to straight-line or molded inlaid material.

In the copending application of Walter F. Kaufman, Serial No. 397,777, filed Oct. 7, 1929, there is described and broadly claimed a process wherein a mask or masks are laid over the surface of the material and compacting pressure applied. The mask is of a thickness corresponding generally to the degree of embossing desired, and when the pressure is applied such mask is forced into the goods. It is later stripped therefrom to leave depressed areas in the material. The present invention is designed to simplify the application of the broad Kaufman invention to the embossing of large areas of goods.

In the case of tile patterns, for example, where it is desired to emboss interliners all over the material, it has heretofore been necessary to use large embossing dies which are made at considerable expense. The embossing operation requires close registration and any change in the pattern, of course, requires that the embossing die be correspondingly changed. I provide for feeding a substantially continuous masked web of material, as, for example, heavy paper, through the compressing means with the linoleum to be compressed. In the case of straight-line linoleum, such as is produced on the well-known rotary machine, there may be provided a die roll, similar to those employed for cutting the webs of linoleum mix into pattern elements and scrap, and operated in synchronism therewith. According to this form of the invention, a continuous web of paper or the like is fed to such die roll and is there cut into a lace-like web which lies over the material in perfect register therewith. When the material passes through the calender, this lace-like web is forced into the surface of the goods, and, after calendering, it is stripped therefrom. This makes it possible to obtain all-over embossing in the rotary machine.

In the case of molded inlaid linoleum, the web may be fed through the "making" press and the consolidation and embossing of the goods simultaneously effected.

The web is preferably made of some non-adherent material, such as oiled paper, so that it will strip readily from the embossed goods and will not mar the surface thereof. Provision is further made for inspecting the material either before or after the embossing, as desired.

In the accompanying drawings, illustrating the present preferred embodiment of the invention and certain modifications thereof,

Figure 1 is a top plan view of a piece of linoleum such as may be embossed by my invention;

Figure 2 is a sectional view thereof to enlarged scale;

Figure 3 is a diagrammatic view of a rotary machine for carrying out my invention;

Figure 3a is a view of the masking web;

Figure 4 is a diagrammatic view corresponding to Figure 3 but showing a modified apparatus;

Figure 5 is a diagrammatic view illustrating my invention as applied to the molded inlaid process;

Figure 6 is a view showing a special pattern element which may be employed;

Figure 7 is a mask therefor; and

Figure 8 is a view showing a preformed special pattern element with the mask of Figure 7 embedded therein.

The material shown in Figure 1 is a tile pattern consisting of square tiles in various colors and having interliners representing mortar joints. It is desired to emboss these interliners so as to give a hand-laid tile effect. Such embossing is clearly shown in Figure 2.

Figure 3 illustrates in diagram a machine of the well-known rotary type modified so as to carry out my invention. In the rotary machine, a backing B of burlap is passed around a large rotary drum 2. Die rolls 3 are arranged around this drum, the die rolls being supplied with webs 4 of linoleum mix from calenders 5. The webs are carried to the die rolls by belts 6 and pass between such die rolls and platen rolls 7. The peripheral surfaces of the die rolls carry knives which cut the webs 4 into pattern elements and scrap, the scrap being 100

discharged by strippers actuated by pin rolls 8 lying within and rotating with the die rolls. The scrap is discharged into troughs 9, and the remaining pattern elements are laid on the backing by strippers actuated by pin rolls 10. Different die rolls apply different colors to the backing, thus making up the pattern. The material travels from the drum 2 to a roll calender 12 where the pattern elements are compressed and consolidated with one another and with the backing.

In order to emboss the interliners of the pattern, I provide a die roll 13 having a platen roll 14 and a pin roll 15 for discharging cut-out scrap. The die roll 13 is fed with heavy oiled paper from a roll 16 and this paper is cut into a continuous lace-like web, as shown in Figure 3a. This paper lies over the pattern and in exact register therewith because the die roll which cuts it is in synchronism with the machine.

As the material travels through the roll calender, the web of paper is forced into the linoleum, embossing it. As it leaves the roll calender the paper web is wound on a roll 17 while the linoleum travels over an inspection table 18.

If it is desired to insert a special inset figure into the linoleum, this may be done on an inspection table 19, lying between the rotary machine proper and the calender 12, by an operator who pulls a pattern element from the uncompressed material through an opening in the paper web and drops a special pattern element in its place. A representative special pattern element is shown in Figure 6. Figure 7 is a corresponding mask therefor. If desired, the special pattern element may be precompressed with the mask, as shown in Figure 8, wherein the mask is represented by the reference character 20. The special figure is thus preliminarily embossed, and this embossing is preserved by the mask 20 as the material travels through the roll calender. The mask of Figure 7 is preferably made of a soft metal which assumes the curvature imparted to it by the roll calender 12 and thus it is "cocked" upwardly from the material as it leaves the calender, as indicated at 21, making the removal of such mask easy.

If it is desired merely to emboss the face of certain pattern elements and not to set special designs or figures into the goods, this may be accomplished by laying small masks on the desired squares of the pattern through the spaces in the lace-like paper web.

In Figure 4 there is shown a modified form of the invention wherein corresponding parts have been given the same reference characters in Figure 3 but with an "a" suffixed thereto. In this form of the invention, the die roll 13a, instead of being arranged on the periphery of the drum 2a, is placed beyond the inspection table 19a and has a backing roll 40 cooperating therewith. The die roll 13a is

driven in synchronism with the drum through suitable gearing, not shown. This arrangement leaves a clear space over the inspection table 19a, where the workmen may get at the goods without being hampered by the lace-like embossing web.

Figure 5 shows the invention applied to the manufacture of molded inlaid material. The molded inlaid machine consists of a bed 50 having pin bands 51 extending therearound, whereby the backing B' is fed along in a step-by-step manner under stencils 52. Granulated color is strickled through the stencils onto the backing, and when the pattern is completed, this granulated material is consolidated under a press 53. The press 53 has a head 54 which moves down on the goods. In order to prevent sticking, oiled paper is fed from a roll 55 under the face of the press and is reeled on the other side at 56. The lace-like web of masking paper is fed from a roll 57 and lies between the protecting sheet of oiled paper and the linoleum mix, whereby upon lowering of the press, this lace-like web is forced into the material and embosses it. As the goods is moved forward, the paper backing and the embossing web are also advanced so as to keep them in registry with the material.

If special figures are to be inserted, the stencils 52 may be so formed as to leave blank spaces on the backing B' into which preformed pattern elements, such as those of Figure 6, may be placed either by an operator alongside the machine or the inspector along the platform 58. If desired, these inset figures may be smooth and the masks simply laid over them, or they may be preliminarily embossed, according to the disclosure of Figure 8, the mask being left in place to preserve the embossing during the compressing step.

Any suitable sheet-like material may be used. A heavy paper has the advantage of cheapness, but if deeper embossing is required, some thicker material may be employed. If the web has a textured surface, such texture will be imparted to the linoleum, thus giving a new and desirable effect.

I have illustrated and described the present preferred embodiment of the invention and certain modifications thereof. It will be understood, however, that it is not limited to the forms shown but may be otherwise embodied or practiced within the scope of the following claims.

I claim:

1. In the method of making embossed inlaid linoleum, the steps consisting in forming pattern elements which are to be compressed and consolidated, feeding the same to a compressing means, together with a substantially continuous perforated web, and pressing the web into the goods during the compressing operation.

2. In the method of making embossed inlaid linoleum, the steps consisting in forming pattern elements which are to be compressed and consolidated, feeding the same to a substantially continuously acting compressing means, together with a substantially continuous perforated web, and pressing the web into the goods during the compressing operation.

3. In the method of making embossed inlaid linoleum, the steps consisting in forming pattern elements which are to be compressed and consolidated, feeding the same to a compressing means, together with a substantially continuous perforated non-adherent web, and pressing the web into the goods during the compressing operation.

4. In the method of making embossed inlaid linoleum, the steps consisting in forming pattern elements which are to be compressed and consolidated, feeding the same to a compressing means, together with a substantially continuous perforated web having a textured surface, and pressing the web into the goods during the compressing operation.

5. In the method of making embossed inlaid linoleum, the steps consisting in forming pattern elements which are to be compressed and consolidated, feeding the same to a compressing means, together with a substantially continuous perforated web, placing individual masks over desired pattern elements in registry with the perforations in such web, and compressing the material.

6. In the method of making embossed inlaid linoleum, the steps consisting in forming pattern elements which are to be compressed and consolidated, moving the material forwardly to a compressing means, cutting a web of masking material as the linoleum moves and laying the same over the linoleum, and pressing the web into the goods during the compressing operation.

7. In the method of making embossed inlaid linoleum in a rotary machine effective for cutting webs of material into pattern elements and scrap and laying the pattern elements on a backing, the steps consisting in thus laying a major portion at least of a desired pattern, cutting a sheet of masking material in synchronism with the laying of the pattern elements and placing the same over the pattern, and compressing the material.

8. In combination with a machine for compressing linoleum and the like, a perforated substantially continuous web adapted to overlie the linoleum during the compressing step.

9. In combination with a machine for compressing linoleum and the like, a perforated substantially continuous web adapted to overlie the linoleum during the compressing step, and means for cutting such web at a rate corresponding to the rate at which the linoleum is compressed.

10. In combination, a calender for lino-

leum or the like having means for supplying a substantially continuous perforated web to the calender over the surface of the linoleum.

11. In combination, a calender for linoleum or the like having means for supplying a substantially continuous perforated web to the calender over the surface of the linoleum, and means for rolling up the web on the exit side of the calender.

12. In combination with a rotary machine for the manufacture of linoleum or the like, the machine having die rolls effective for cutting webs of linoleum mix into pattern elements and scrap and laying such pattern elements on the backing, a die roll, and means whereby a web of masking material is supplied thereto.

13. In combination with a rotary machine for the manufacture of linoleum or the like, the machine having die rolls effective for cutting webs of linoleum mix into pattern elements and scrap and laying such pattern elements on the backing, a die roll, and means whereby a web of masking material is supplied thereto, said die roll lying further around the periphery of the rotary machine than that die roll which applies pattern elements.

14. In combination with a rotary machine for the manufacture of linoleum or the like and having die rolls effective for cutting webs of linoleum mix into pattern elements and scrap and laying the pattern elements on a backing, a die roll for cutting masking material, and means for guiding the masking material so as to leave it free for inspection.

15. In the method of making embossed inlaid linoleum, the steps consisting in forming pattern elements which are to be compressed and consolidated, placing a substantially continuous perforated web over the face of the goods, placing a perforated mask over a portion of the surface of the goods and at an opening in the web, and feeding the goods forward together with the web and the mask to a compressing means and thereby subjecting them to pressure to effect embossing of the goods.

In testimony whereof I have hereunto set my hand:

HARRY S. HUMPHREYS.
